UNITED STATES PATENT OFFICE.

GEORGE M. PETTENGILL, OF HAVERHILL, MASSACHUSETTS.

HEEL-NAILING MACHINE.

No. 861,051.

Specification of Letters Patent.

Patented July 23, 1907.

Application filed January 4, 1907. Serial No. 350,850.

To all whom it may concern:

Be it known that I, GEORGE M. PETTENGILL, of Haverhill, county of Essex, State of Massachusetts, have invented an Improvement in Heel-Nailing Machines, of which the following description, in connection with the accompanying drawings, is a specification, like characters on the drawings representing like parts.

In heel nailing machines it has been customary to form nail holes in the heel with a series of awls previous to driving the nails, this operation being generally known as "pricking" the heel, but in the machines now generally employed this operation has been eliminated, with the result that the time in which the whole heel operation may be performed is reduced by about one-third. While the preliminary pricking of the heel is not an essential in most instances, yet it is nevertheless desirable in all instances, for the reason that the danger of the nails being crippled or bent, while they are being driven through the heel to clench them, is to a great extent avoided, the crippling of the nails being of frequent occurrence when the heels are not previously pricked. Moreover if the nail holes are not formed previous to driving, it frequently happens that some of them are so deflected or driven in a direction other than that desired, that they are forced out through the side of the heel or are driven so close to the surface that they are encountered by the heel shaving cutter, much to the detriment of the latter. In such instances it is often necessary to remove the heel and attach a new one.

The principal object of my invention is to provide a heel nailing machine with means whereby the heel may be pricked previous to nailing without materially increasing the number of operations necessary to attach its heel and top lift, or the time consumed in performing the whole operation.

In nailing on heels, and particularly high, and what are known as "fancy" heels, it is not only difficult to drive the nails so that they will pass completely through the heel, without previously pricking it, but it is often desirable that the nails be driven obliquely to the face of the heel to correspond with the inclination of the breast thereof. While guiding devices have been provided which are supposed to cause the nails to be driven at the desired inclination, yet these devices are not uniformly effective, and are disadvantageous for reasons which need not be here explained.

In this connection, a further object of my invention is to provide means whereby the nail holes in the heel may be formed by the awls at different inclinations to the face thereof, so that the nails will be necessarily driven in the desired direction for a considerable portion of their length, the possibility that they will thereafter be deflected being very remote.

Further objects of my invention are to improve prior forms of heel machines in certain more minor particulars which will hereinafter appear.

I accomplish the principal object of my invention, above referred to, by providing means whereby one heel will be pricked simultaneously with the operation of spanking the top lift onto another heel already attached to a shoe, and I accomplish the second object of my invention by providing means whereby the inclination at which the heel is held with relation to the path of the awls may be varied, so that the direction of the nail holes with relation to the face of the heel may be correspondingly varied.

For a more complete understanding of my invention reference is made to the accompanying drawing, in which,

Figure 1 is a front elevation of a machine made according to that invention. Fig. 2 is a vertical section thereof on the line *a—a* of Fig. 1. Figs. 3 and 4 are detail views in plan and front elevation, respectively, of the heel holder. Fig. 5 is a rear elevation of the heel carrier and awl mechanism. Fig. 6 is a plan view of the machine. Fig. 7 is a detail view of the heel carrier mechanism taken on the line *a—a* of Fig. 1. Fig. 8 is a plan view of the carrier slide. Fig. 9 is a detail sectional view on the line *b—b* of Fig. 6. Figs. 10, 11 and 16 are enlarged detail views on the line *a—a*, Fig. 1, showing the parts in different positions. Fig. 12 is an enlarged detail view on the line *c—c* of Fig. 6. Fig. 13 is a similar view on the line *d—d* of Fig. 6. Figs. 14 and 15 are detail, plan and side elevations of the top lift holder. Fig. 17 is a detail view of the nail plate. Fig. 18 is a detail view on line *e—e* of Fig. 12.

The general type of machine shown, to which I preferably apply my invention, is of that class known as the vertically movable cross head and turret type, although many of the features thereof may be applied to machines of other types.

The main frame 1 of the machine has the driving shaft 2 journaled therein, and said shaft is connected to the crank shaft 3 by means of intermediate gears 4, 5, 6 and 7, so that the operating plunger 8 will be constantly raised and lowered when shaft 2 is driven. A vertically movable cross-head 9 is mounted on the lower ends of the side rods 10, on the upper ends of which the upper cross-head 11 is also mounted. Springs 12 are arranged on said rods 10 and act between lugs 13 upon the frame and collars 14 upon the rods 10, to hold the cross heads in their uppermost position. A bar 15 is adapted to be moved between the lower end of the plunger 8 and the cross-head 9 by means of the treadle 16 and intermediate gears 17 and 18 and arm 19, so as to form a connection between the plunger and the cross-head. That is, when the treadle 16 is depressed the bar 15 is moved rearwardly from the full line posi-

90

80

85

100

105

110

tion of Fig. 2, so that when the plunger 8 descends it will engage the bar 15 and force the cross-heads downwardly against the action of the springs 12.

The bed 1' of the frame is provided with guide-ways 5 in which the jack 20 is slidably mounted, said jack being of ordinary form and forming no part of my invention. A base piece 100 is mounted on the bed in the rear of the jack and the nail plate holder 21 is mounted directly thereabove, said holder having a guide rod 22 10 connected to the under side thereof which passes down through said base piece and is adapted to slide vertically therein. A supporting spring 23 is mounted on said rod 22, and is arranged between the under side of the holder 21 and said base piece, and a guiding extension 210 is formed integral with said holder which extends upward from the main body thereof and is held to slide between guide-ways 24 on the rear side of the upper cross head 11. A hand lever 25 is pivoted on the base piece 100 and is connected by a link 26 to the 20 holder 21, so that the latter may be drawn downwardly by said lever against the action of the spring 23, said rod 22 and extension 210 forming effective guiding means therefor.

A heel holder 27 is disposed directly in the rear of 25 the jack 20, and is mounted on a support 28, which is in turn supported rigidly on a vertical adjusting screw 29, the latter being threaded into a nut 30 mounted on the upper side of a bracket 31, so that by turning said nut said holder may be vertically adjusted. The bracket 30 31 is mounted in guide-ways formed in the base piece 100, so that it may be adjusted to and from the jack, an adjusting screw 32 being provided therefor which has a swivel connection with the base piece 100, and a threaded connection with a depending lug 310 formed on the 35 under side of the bracket 31. The holder 27 is pivotally connected at its front end to the support 28 by means of a horizontal pin 33, extending transversely of the jack, so that said holder may be adjusted horizontally or inclined rearwardly. A set screw 34 is 40 threaded in the support 28 and bears against the under side of the holder 27 adjacent the rear end thereof, so that the inclination of said holder may be varied by raising or lowering said screw 34.

A plate 35, having a convex projection thereon, corresponding to the usual depression formed in the heel, 45 is mounted in a dovetail slot formed in the upper side of holder 27, so that it may slide horizontally to and from the jack, said plate being provided at its rear end with a pair of upwardly extending lugs 37 which are 50 adapted to engage the rear edge of the heel to hold the same from rearward movement. An adjusting screw 38 is threaded in the holder 27 and a depending lug 39 on the rear end of plate 35, has a swivel connection therewith, so that said plate may be adjusted forwardly 55 or rearwardly thereby.

A pair of brackets 40 are mounted to slide transversely of the jack in a dovetail groove formed in the front side of the support 28 and a screw 41, having right and left threads respectively engaging said brackets, is provided 60 for adjusting said brackets to and from the middle of the jack. Spring guiding arms 42 are mounted on said brackets 40 in position to guide and hold the shoe centrally on the jack and a buffer 43 is provided on said support between said arms.

65 A turret 44 is mounted in the cross-head 11 of the ma-

chine and said turret is provided with two arms 45 and 46. The arm 45 carries the driver head 450 having the usual drivers 47; and a snort driver or finger 48, and the arm 46 carries the top lift holder 49. These devices on the turret, with the exception of the finger 48, are substantially the same as those well known in the art, the top lift holder being provided with a pair of spring guiding arms 50 which are adapted to grasp the top lift and hold it in the desired position, and an adjusting screw 51, see Figs. 14 and 15, being provided for adjusting the 70 arms 50 according to the width of the top lift. The shaft 52 on which the turret 44 is mounted, is provided on its rear end with the pinion or gear 53, which is adapted to mesh in the rack 54 formed on the awl holder guiding plate 55, said plate being held and adapted to 75 move vertically between the cross-head 11 and the extension 210 of holder 21 and between guide-ways 211 formed in the rear side of said extension. An awl holder 56 has a series of awls 57 and a short plunger 58 mounted therein, and is removably connected to the bottom face 80 of a head 550 formed integral with the guiding plate 55 at its lower end. Said awls are thus arranged to be 85 adjusted vertically independently of the cross-head by rotating the turret shaft, and to be moved vertically with said cross head directly over the heel holder 27. 90 A lug 460 on the top lift holder arm 46 is adapted to engage the upper side of the head 550 under certain conditions hereinafter referred to. The usual locking latch 59 and actuating arm 60 for the turret 44 are provided.

The nail plate 61 is mounted to slide horizontally in the holder 21, said plate being provided with an upwardly extending handle 62 at its rear end, as shown in Fig. 2. The front end portion of said plate is provided with the usual nail holes 63 arranged to correspond with the gang of drivers which are to be employed. A plate 610 is secured to the under side of the nail plate 61 at the front end thereof and is provided with apertures in register with the nail holes 63. One or more brads 64 are secured in the plate 610 at suitable points 105 and project a short distance below the under surface thereof, and a pair of brads 65 are mounted to slide vertically in plate 610 adjacent the middle thereof. Said brads 65 are suspended by their heads in a sleeve 66 which is slidably mounted in a hole 67 through the nail plate of corresponding size, said sleeve resting on the end of a lever 68 when in its lowest position. Said lever 68 is pivoted to the nail plate 61 in a recess 69 formed therein adjacent the plate 610 and an aperture 70 is provided in the nail plate in a line with the front 110 end of said lever 68, the rear end thereof being adapted to extend beneath the sleeve 66 so that when the front end of said lever 68 is depressed the rear end thereof will lift the brads 65. The short plunger 58 is arranged to enter the hole 67 of the nail plate to engage the heads 115 of the brads 65, and the short plunger 48 is arranged to enter the hole 70 thereof to engage the lever 68, under conditions which will hereafter be explained.

A circular nail holding plate 71 is mounted in a circular recess on the upper side of a bridge piece 72 rigidly secured to support 21, and two or more series of nail holes 73 are provided in said plate as indicated in Fig. 17, arranged so that one series will not interfere with the other, whereby said plate may be turned to bring the different series into register with a particular series of 120 125 130

nail holes 63 in the nail plate. A locking pin 74 is provided to hold the plate 71 in different positions, as shown in Fig. 13. A plate 75 is adapted to be secured to bridge piece 72 above the plate 71, and is provided with a series of nail holes corresponding to the particular series of holes to be used in said plate 71. One plate 75 must obviously be provided for each series of holes.

A nail supporting slide 76 is mounted directly beneath the plate 71 and is movable in guideways formed 10 in the base piece 72 and a U-shaped spring 77 is connected at one end to said piece 72 and at the other to the slide 76, said spring being adapted to withdraw the slide from beneath the nail holes in plate 71. A lip 78 on the end of the slide is adapted to engage a cross bar 15 79 beneath the slide and secured to piece 72 to limit the movement thereof by said spring. An angular lever 80 is pivoted at 81 to the bridge piece 72 and a locking pin 82 is mounted in said piece 72 and movable vertically therein, one end of said lever being pivotally 20 connected to said pin, and said lever being balanced to permit said pin to drop into a hole 83 in the slide 76 to lock the latter in its innermost position, see Fig. 18. A pin 84 is mounted in the nail plate in position to engage the opposite end portion of said lever 80 from locking pin 82, said end portion extending below the pivot 81 and being bent obliquely at its end as shown in Fig. 6, so that when pin 84 engages the oblique surface at said end it will push the same transversely of the nail plate, causing the opposite end of lever 80 to be raised 25 30 withdrawing said locking pin from the hole 83 in the plate, so that the spring 77 may act to withdraw it from beneath the holes 73 of the nail holder plate 71. Pin 84 is so located that this action takes place just before the nail plate 61 is withdrawn to its rearmost position.

35 A spring finger 85 is secured to one side of the holder 21 and a pin 86 is secured in the end thereof and extends at opposite sides of said finger. One end of said pin extends through the sides of the nail plate guideway of the holder 21, so that when the nail plate 61 is in one 40 of the three positions to which it is moved in the course of operation, said spring arm will force said pin 86 into one of three recesses 87, 88 and 89 formed in the adjacent edge of the nail plate. Said recesses 88 and 89 are inclined rearwardly from the bottom thereof to the 45 edge of the plate, so that, when the plate is moved inwardly, the pin 85 may slide therefrom, thereby permitting forward movement of the plate without withdrawing the locking pin 86.

A fixed rod 90 is mounted in the base piece 100 and 50 extends through a lug 91 mounted on the support 21. The function of this rod is to prevent the holder 21 from being moved down when the nail plate is not in one of the three positions in which it may be locked and to prevent the assistant of the operator from moving the 55 nail plate when the latter is in any position but its uppermost position. When the inner end of the pin 86 is in one of the notches 87, 88, or 89 and the holder 21 is held down, then the pin 86 cannot be moved out of its notch to permit the plate 61 to be moved, as such movement is prevented by rod 90, which will engage the outer end of pin 86. When the pin 86 is in its outer position, to permit the plate 61 to slide, then the outer end of said pin will engage the upper end of rod 90 and prevent the holder 21 from being lowered.

65 Before operating the machine, the jack will be verti-

cally adjusted according to the height of heel to be attached, and the holder 27 will also be correspondingly adjusted. In this connection it will be noted that the adjustment of the holder 27 also accomplishes the adjustment of the guiding fingers 42 which are ordinarily 70 adjusted independently of the jack.

On starting to operate the machine the nail supporting plate 76 will be locked in its inner position shown in Fig. 7, and the turret will be turned until the top lift holder is in position over the jack, this movement 75 permitting the awl holder 56 to be lowered to its lowest position, as indicated in Fig. 11. The nail plate is moved to its middle position, so that the nail holes 63 therein are directly over the holder 27, and the pin 86 is in the middle recess 88 of the plate 61. A heel is then 80 placed on top of the holder 27 so that its back edge rests against the fingers 37 and the holder 21 is lowered, pressing the plate 61 on the heel. The treadle 16 is then operated and the cross head is lowered carrying down the awl holder 56, so that the awls pass through the holes 63 85 in the nail plate and enter the heel and forms the nail holes therein, or "prick" it, as indicated in Fig. 11. Simultaneously with this operation the short brads 64 will be forced into the heel and the plunger 58 will engage the heads of the awls 65 and drive them into the 90 heel for a considerable distance.

The parts are so arranged that when the turret is rotated to the position of Fig. 11, the lug 460 on the arm 46 will bear against the upper side of the head 550, so that the force which it takes to drive the awls into the 95 heel will be communicated thereto from the cross head through said lug, as well as through the pinion 53.

It is often desired to have the nails driven slightly obliquely to the surface of the heel, as well as perpendicularly, and, in order that they may be driven at 100 any degree of inclination desired the above described means for varying the inclination of the holder 27 is provided, such variation being accomplished by turning the screw 37, so that the face of the heel may be held at the desired angle to the path of movement of the awls, 105 causing the awls to pass into and partly through the heel at a corresponding angle. In practice it is only necessary to incline the holes from front to rear inwardly, so that there is practically no tendency to force the heel forwardly while it is being pricked, the 110 stops 37 being sufficient to hold the heel in position.

The above described action of driving the awls 65 and brads 64 into the heel, causes the heel to become attached to the bottom side of the plate 610, so that when the nail plate 61 is raised, as the cross head is lifted, 115 the heel will be lifted from the holder. It will be noted that the nail plate, at this point, acts to hold the heel while the awls are withdrawn therefrom. The operator's assistant then withdraws pin 86 from notch 88 and draws the nail plate 61 rearwardly until the holes 63 120 therein are in register with the holes 73 in the nail holding plate 71, and further rearward movement is prevented by the engagement of the pin 86 with the plate in recess 89. As the nail plate reaches its rearmost position, the pin 84 will swing the lever 80 so as to withdraw the pin 82 from the hole 83 in the nail supporting plate 76, to permit the spring 77 to withdraw said plate 76 from beneath the nails which have already been placed in the holes 73. This action permits the nails to fall into the holes 63 of the nail plate and also into 130

the nail holes which have been formed in the heel, as indicated in Fig. 16. The assistant then pushes the nail plate forwardly until the heel is held directly over the jack and the holes 63 are in line with the path of the drivers, the pin 86 entering the recess 87 to lock the plate in this position. During the latter part of this motion the handle 62 on the plate engages the nail supporting slide 76 and forces the same into its normal position beneath the holes in the plate 71, so that the pin 10 82 may fall into the hole 83 therein to lock it in place, as shown in Figs. 3, 7 and 18. While this operation has been taking place the operator will have turned back the turret, so that the drivers are in position over the jack, the consequent rotation of the turret shaft 15 causing the pinion 53 to lift the awl holder 55 to its uppermost position, as shown in Fig. 10. The plate holder 21 is then lowered to press the nail plate against the heel, the foot lever 16 is operated and the cross head is lowered so that the drivers 47 pass through the nail 20 plate and engage the heads of the nails and force them through the heel to attach it in the ordinary manner. During this movement the awls are only carried down to points just above the upper surface of the nail plate, see Fig. 10. Just before the end of this motion is 25 reached the short plunger 48 will engage the end of the lever 68 and force the same downwardly, so that its opposite end will engage the sleeve 66 and force it upwardly withdrawing the brads 65 from the heel.

It may be here stated that the purpose of using two 30 brads 65 instead of one, is that, if only one were employed, and if it should strike the nail ordinarily used to attach the lifts of the heel together, the brad would probably fail to attach the heel firmly to the nail plate, but it would be unlikely to happen that more than one 35 of these brads would strike a nail which would prevent the heel from being firmly attached. The brads 64 also assist in attaching the heel to the nail-plate, and, furthermore, all of these brads perform the important function of holding the heel rigidly in place under the 40 nail plate while the drivers are forcing the nails through the heel and clenching them against the bottom of the last. It frequently happens that a heel slips to a slight extent with relation to the nail plate as the nails strike the iron bottom of the last, so that the ends of the 45 nails which should be left upright to enter the top lift are bent obliquely to such an extent that it is not possible to secure the top by spanking it on, necessitating the attachment of a new heel. The holding brads, above described effectively prevent horizontal movement 50 or slipping of the heel under the nail plate, so that the nails are driven in as far as they should be and their ends are left upright, thereby entirely avoiding the difficulty above referred to.

The brads 65 having been almost wholly withdrawn 55 by the action of the short driver 48, and the brads 64 being short, when the nail plate is raised at the end of the driving operation and upon the withdrawal of the drivers, said brads will readily become disengaged from the heel. The operator's assistant then unlocks 60 the nail plate and withdraws it until it is stopped in its middle position over the nail holder by the entrance of pin 86 into recess 88. The operator releases the catch 59 of the turret as soon as the cross head is raised, so that the actuating lever 60 rotates it to carry the top lift-holder down to the jack, a top lift having previously 65

been placed in said holder, and, while the turret is turning, he places another heel upon the holder 27, so that when he again moves the foot lever 16 to cause the cross head to descend the top lift will be spanked upon the heel which has just been attached and at the same time 70 the new heel, which has been placed in the holder 27, will be pricked by the descending awls, as before described, said awls having been lowered to their operative position by the rotation of the turret to bring the top lift holder into its operative position. The above 75 described operation will then be repeated, the heel being attached by one motion of the cross-head, and the top lift being spanked on and the next heel being pricked simultaneously by the next motion of the cross-head. 80

Having thus described my invention, what I claim to be new and desire to secure by Letters Patent is:—

1. A heel nailing machine comprising heel attaching, top lift attaching and heel pricking means, and operating means therefor permitting alternate operation of said attaching means, and simultaneous operation of one of said attaching means and said pricking means, substantially as described. 85

2. A heel nailing machine comprising heel and top lift attaching means and means whereby they may be successively operated, heel pricking means, and means for operating said pricking means simultaneously with one of said attaching means and for rendering it inoperative while the other attaching means is operating, substantially as described. 90

3. A heel nailing machine comprising heel attaching, top lift attaching and heel pricking means, means permitting movement of said heel and top lift attaching means into and out of operative position successively, and means for moving said pricking means into and out of operative position upon corresponding movement of one of said attaching means, substantially as described. 95

4. A heel nailing machine comprising heel attaching, top lift attaching and heel pricking means, means permitting movement of said heel and top lift attaching means into and out of operative position successively, and means for moving said pricking means into and out of operative position upon corresponding movement of said top lift attaching means, substantially as described. 100

5. A heel nailing machine, comprising a movable operating head, heel attaching, top lift attaching and heel pricking means mounted on said head, means permitting movement of said attaching means into operative position successively and means whereby one of said attaching means will be caused to operate upon one movement of the head and the other attaching means and said pricking means will be caused to operate upon a succeeding movement of the head, substantially as described. 110

6. A heel nailing machine comprising a movable operating head, heel attaching, top lift attaching and heel pricking means mounted on said head, means whereby said attaching means may be successively moved into and out of operative position, means connecting one of said attaching means and said pricking means for moving said pricking means into and out of operative position upon corresponding movement of said attaching means, whereby one of said attaching means may be operated upon one movement of the head and the other attaching means and the pricking means may be operated upon a succeeding movement of said head, substantially as described. 120

7. A heel nailing machine comprising a vertically movable head, a turret mounted thereon, a series of drivers, and a top lift holder mounted on said turret, a series of awls mounted on said head, a heel holder adapted to hold the heel in position to be pricked by the awls when the head descends, connections between said awls and said turret whereby movement of said turret to one operative position will move the awls to an inoperative position and movement of the turret to its other operative position will move the awls to an operative position, substantially as described. 130

8. A heel nailing machine comprising a jack, a verti-

- 5 eally movable head, a turret mounted thereon, a series of drivers and a top lift holder mounted on said turret and successively movable into operative position over said jack upon rotation thereof, a heel holder, an awl holder vertically movable on said head over said heel holder, connections between said awl holder and said turret for lowering said awl holder into operative position upon rotation of the turret into one operative position, and for raising it to an inoperative position upon rotation of the turret to the 10 other operative position, substantially as described.

9. A heel nailing machine comprising heel and top lift attaching means and means whereby they may be successively operated, a heel pricking means, means for operating said pricking means upon one heel while one of said attaching mechanisms is operating upon another heel, and means for transferring the heel from said pricking means to said attaching means, substantially as described.

15 10. A heel nailing machine comprising a jack, a heel holder adjacent thereto, a series of awls for forming the nail holes in the heel when held by said holder, means for transferring the heel from said holder to said jack, means for attaching the heel to the shoe while held over said jack, top lift attaching means, means whereby said heel and top lift attaching means may be successively operated, and means for operating said awls upon one heel during the 20 time of operation of one of said attaching means upon another heel, substantially as described.

25 11. A heel nailing machine comprising a jack, a heel holder adjacent thereto, a nail plate movable to predetermined positions over said holder and said jack, a series of awls, means for moving said awls through said plate to form nail holes in a heel held on said holder, means for simultaneously attaching the heel to the face of the plate, means permitting movement of the plate to carry the heel into position over the jack and means for driving the nails to attach the heel while held in the latter position, substantially as described.

30 12. A heel nailing machine comprising a nail plate having a heel-engaging brad on the face, means permitting movement of said plate to press the heel against the heel seat of the shoe, means for driving the nails to attach the heel and means for disengaging the brad from the heel while the plate is in engagement therewith, substantially as described.

35 13. A heel nailing machine comprising a nail plate having a heel-engaging brad on the face, means permitting movement of said plate to press the heel against the heel seat of the shoe, means for driving the nails to attach the heel while held from transverse movement by said brad, and means movable independently of the plate for withdrawing said brad from the heel at the end of the nail driving operation, substantially as described.

40 14. A heel nailing machine comprising a nail plate, a projection on the underside thereof, a heel holder, means for forcing said plate into engagement with a heel held by said holder to cause said projection to enter the heel to attach the heel to the nail plate, a jack and means permitting movement of the nail plate to carry the heel in position over the jack and to press it against the heel seat 45 of the shoe, means for driving the nails to attach the heel while thus held, and means for moving the brad independently of the plate to disengage it from the heel, substantially as described.

50 15. A heel nailing machine comprising a jack, a heel holder adjacent thereto, a nail plate, heel-engaging means 55 on said plate, a series of awls, means for simultaneously forcing said awls into a heel held by said holder and operating said engaging means to connect the heel to said plate, means permitting movement of said plate to carry the heel into position over the jack, a driver head, means for moving said head to fasten the heel to the shoe and means for moving said heel-engaging means to disconnect the heel from the plate, substantially as described.

5 16. A heel nailing machine comprising a jack, a heel holder adjacent thereto, a nail plate, heel-engaging means 70 on said plate, a series of awls, means for simultaneously forcing said awls into a heel held by said holder and operating said engaging means to connect the heel to said plate, means permitting movement of said plate to carry the heel into position over the jack, a driver head, means for moving said head to fasten the heel to the shoe and means carried by said driver head for moving said heel-engaging means to disconnect the heel from the plate during the driving operation, substantially as described.

15 17. A heel nailing machine comprising a jack, a heel holder adjacent thereto, a nail plate having a longitudinally movable attaching brad mounted therein, a series of awls, means for simultaneously forcing said awls and said brad into a heel held by said holder, means permitting movement of said plate to carry the heel into position over the jack, a series of drivers, means for operating said drivers to attach the heel and for simultaneously lifting said brad to disconnect the same from the heel, substantially as described.

20 18. A heel nailing machine comprising a jack, a heel holder adjacent thereto, a nail plate having an attaching brad mounted therein and movable beyond the face of the plate to enter the heel, lifting devices for withdrawing the brad from the heel, a series of awls and means for simultaneously driving said awls and said brad into a heel held by said holder, a series of drivers and means for simultaneously operating said drivers and said lifting devices, substantially as described.

25 19. A heel nailing machine comprising a heel holder, a series of awls, means for forcing said awls into a heel held by said holder to form nail holes therein, and means for varying the inclination of said holder to vary the inclination at which the nail holes are formed, a jack, and means for transferring the heel from the holder to the jack in position for attachment after the nail holes have been formed, substantially as described.

30 20. A heel nailing machine comprising a bed, a vertically movable cross head having vertical guide-ways formed therein, a vertically movable nail plate holder having horizontal guide-ways and a nail plate mounted therein, a guiding support for the rear end of said plate holder mounted in the bed, an extension rigidly connected to the front end of said holder slidably mounted in the guide-ways of said cross head, a jack, a heel holder disposed in the rear of said jack and beneath said plate holder extension, an awl holder supported by said cross head above said heel holder, and heel and top lift attaching devices carried by said cross head over said jack, substantially as described.

35 In testimony whereof, I have signed my name to this specification, in the presence of two subscribing witnesses.

40 GEORGE M. PETTENGILL.
